(57) **CLAIM**

I claim the ornamental design for a baby carrier cover, as shown and described.

DESCRIPTION

FIG. 1 is an upper perspective view of the baby carrier cover showing my design.

FIG. 2 is a side view thereof;

FIG. 3 is an opposite side view thereof;

FIG. 4 is an end view thereof;

FIG. 5 is another end view, showing an open position of a pocket; and,

FIG. 6 is another perspective view thereof.

The broken lines are presented for illustrative purposes only and form no part of the claimed design.
